MEANS FOR BALANCING WINDOW SASHES

Gilbert L. Huff, Chicago, Ill., assignor to Rock Island Sash and Door Works, Rock Island, Ill., a corporation of Illinois

Application March 30, 1938, Serial No. 198,947

5 Claims. (Cl. 16—198)

The present invention relates to window balances of the spring-actuated type.

The advent of thin walls in modern houses makes necessary the use of thin windows, and it 5 is difficult to provide therein the usual sash weights. The present invention provides an improved sash balance for use in thin windows.

The object of the invention is to provide a balance suitable for thin window-frames, which 10 is easily inserted in the head of the frame, which does not greatly weaken the head of the frame; which may be off the center line of the sash; which serves both cords of a sash; which is self-adjusting in installing to equalize tension; which 15 is easily put and held in tension; which is protected from damage by settling of dust and the like thereon after installation; and which is simple in construction and relatively inexpensive.

Various other and ancillary objects and advantages of the invention will be apparent from the following description and explanation of the device and installation thereof shown in the accompanying drawings, in which:

Fig. 1 is a window equipped with a balance for 20 each sash thereof.

Fig. 2 is a plan view of the window of Fig. 1 on line 2—2 thereof, showing the location of the balances off-center from the sashes, in the window-frame head.

Figs. 3, 4, 5 and 6 are various devices used for 30 attaching wire cord or cable to the sash.

Fig. 7 is a face view of a balance looking at it, as it appears in looking at Fig. 1, on line 7—7 of Fig. 2.

Fig. 8 is an enlarged cross-section of the window of Figs. 1 and 2 showing two balances with 35 detail, the view being taken on line 8—8 of Fig. 2.

Fig. 9 is a perspective view of axial parts to be 40 assembled in producing the balance.

Fig. 10 is a front elevation of a pulley fixture shown generally at the right in Fig. 1 which goes with each balance, when used for both cords of a sash.

Fig. 11 is a cross-section of the pulley fixture of Fig. 10 taken on line 11—11 of Fig. 10.

Fig. 12 shows in perspective the casing parts of the pulley fixture.

It will be understood that the invention is not 50 limited to the exact forms and combinations disclosed in the drawings, and that the invention is subject to numerous modifications and changes within the scope of the appended claims.

In Fig. 1 there is shown a window having interior trim 10, concealing the window frame hav-

ing sides 11 and 12, terminating in horns 13 and 14, and head member 15 set into a receiving groove in each side member 11 and 12. Lower and upper sash 16 and 17 are shown, each operated by its respective balance 18 and 19 (Fig. 2). At the head on the underside is a parting stop 20 (Fig. 8), set into a groove 21 therefor in the head, and the parting stops 22 set in the frame sides 11 and 12.

Referring to Fig. 2 and Fig. 8, it will be seen 10 that the two balances 18 and 19 are respectively further inward and outward from the center lines of the sashes giving a wider space between them in the head 15 in the vicinity where it is weakened by groove 21. Because each balance is 15 set into a recess cut into the head, the width of this space is important in preserving strength in the head, and the thinner the balance is, the greater is this advantage. The construction of the balance permitting this off-center location is 20 therefore an important feature.

The balance itself is completely housed on the upper side so that dust, dirt and plaster cannot collect on it to damage it. On the down-side, where it is flush with the inside surface of head 25 15, it is open. The open character permits affixing the cords, tensioning the spring, and free play for the cords.

The casing is best shown in Fig. 9 as having an arch plate 25 providing a mounting end 26 flush 30 with the frame side 11, and a right-angular mounting end 27 flush with the underside of the head 15, with an upset brace portion 28.

The arch plate 25 is held between two face plates or caps 29 and 30, each having flanged 35 edges 31 and 32 to receive the edges of the arch plate 25. Tongues 33 on the arch plate fit slots 34 in the caps, and are bent over to assemble the parts permanently. A fixed hollow split post 35 extends from face 29 to 30, to each of which 40 it is secured similarly by tongues 35 and slots 37. Thus the post holds the central parts of the caps in a fixed position. The slot in the post is designated 38.

Post 35 acts both as an axle for drum 40 and 45 as a fixture for one end of a spiral spring 41 inside the drum. The drum 40 is formed by an annular member formed integrally with a larger toothed disk 42, and may be made as a die-casting with appropriate detailed structures. The 50 periphery of drum 40 is of less diameter than the toothed disk, so that the latter provides a flange for one end of the drum, to guide the cable and to keep it on the drum in winding. The open face of the said casting has cover 43 providing a 55

flange on the other end of the drum. It is secured to the drum by inserting the die-cast pins 44 of the drum into registering holes 45 in the cover, and upsetting or spreading them as rivets. Thus the drum is well sealed. Cover 43 has an inclined lip 47 (Fig. 8) providing a bevelled flange for the drum, and an upset or dished part 48 surrounding hole 46, which hole bears on post 35. The dished portion extends toward the cap 10 on casing face 30, and between the two a fiber friction disk 49 is placed.

The drum (Fig. 7) has two inner projecting parts 50 (of which only one is used at a time) adapted to engage the hooked end 51 of spring 41, the other end of which has a rounded loop or eye 52 fitting inside the hollow post 35, thus securing it to the axle or post. Thus by simply turning the drum counter-clockwise in Fig. 7, the spring is placed under tension. A gravity operated detent 53 has a slot 54 through which passes a headed rivet 55 to secure it loosely for motion onto rear plate or cap 29. The detent has teeth 56 to mesh with toothed disk 42. The latter is toothed over its entire periphery as a gear so that it may be arrested at any position by moving detent 53 into engaging position. Force of the spring to turn the drum 40 clockwise in Fig. 7 holds the detent in engaging position, but any movement counter-clockwise of the drum will easily let the detent fall automatically by gravity into its normal or non-holding position. This facilitates resetting the device in tension, and using the balance, even when it is installed. The detent also serves as a guide to keep cable from running onto the tops of the flange teeth. An important feature of the detent is its ability to hold the drum in factory-wound tension of a predetermined degree. The detent need not be released from the pre-wound drum until the device is installed and the weight of the window exerted on the drum. The balance may thus be pre-wound for given weights of window, and so marked, to assure perfect operation. Anyone may install the device with ordinary tools and without exercise of judgment on tension.

On the outside of the drum certain peripheral portions are removed to leave projecting parts 57, one of which need not be used. Two parallel holes 58 (Figs. 7, 8 and 9) are formed through 50 the projecting part, generally parallel with a tangent line to the drum surface, but inwardly of it, for the receipt of cable wire 59. Preferably one cable length 59 is used for one sash, an intermediate portion being looped at 60 after passing 55 through holes 58, providing the two lengths of cord for each sash. The position of the loop is easily shifted in installing it and may be automatically located by tensioning the cords after the ends are fastened to the sash. It is also to 60 be understood that each of the cord-blocks 57 may be used where it is desired to have two separate lengths of cord. It is also worthy of mention that the drum 40 may be moved to bring to the open face of the casing, either cord-block 57 65 where it is readily accessible to attach or loop a cord, even when the balance is already installed.

As shown in Fig. 7, the single cable, looped at 60 has one length 59 delivered from the drum sufficiently close to the frame side 11 to run directly 70 to the lower sash 16 for attachment at 61. The other length provides cable 62 for the other side of the sash, and to keep it aligned just below the inside of head 15, a wooden pulley or cylinder 63 is located in the balance on axle pin 64 between 75 the facial caps 29 and 30. Cable 62 is shown at-

tached to lower sash 16 at 65 after passage through pulley fixture 66. It is particularly to be observed that the drum as mounted in the casing, is fully above the underside of the head 15. Thus it is free from being struck by a sash. 5 Although the idler is slightly below the casing cap 29 (see Fig. 7) to deliver cable 62 free from rubbing, the cable itself really takes the force if the top of a sash is raised to the head. For the upper sash balanced by such a device, the top 10 sash member may be slightly recessed to receive any projecting parts of the devices herein described.

In order to keep the head space clear for raising the lower sash to the top, and for accommodating the closed upper sash, the pulley fixture 66 is provided to carry cords 62 up into the head to come down alongside the frame side 12, like the cords 59. A suitable fixture is shown in Figs. 10, 11 and 12.

Because the preferred cable is a bronze or stainless steel single or multiple strand cable of numerous fine sizes of wire, the same is subject to acquiring a permanent curl if a small size of pulley is employed for a substantial turn. 20

In the pulley fixture 66 a sufficiently large diameter of pulley is employed to assure no permanent set in the cable. Two slightly grooved pulleys 70 and 71 of hard wood are preferred, and are located to center the cable with the sash. Being thinner than the companion balance, it is preferably centered with the sash, where the balance is not, and the same order of spacing exists at the paired pulley fixtures as at the paired balances to keep the strength of the head 15, near 35 the groove 21 therein.

The fixture is designed for self-threading of the cable into and out of the fixture by merely pushing it along. Two face plates 72 and 73 have flanges 74 and 75 which engage over the double-arched plate 76. Arched plate 76 has tongues 77 which fit into gaps 78 in the flanges 74 and 75, some or all of the tongues being bent over the plates 72 and 73 to clamp them together. Pulleys 70 and 71 are mounted on pins 79 set in the face 45 plates. Between the pulleys, the face plates 72 and 73 are upset towards each other to provide a narrow space between upset faces 80 to guide cable 62 to the center of the fixture in line with the grooves of the pulleys. Plates 72 and 73 at 50 the open face of the assembled casing have abutting spacing lugs 81 and 82. Arched plate 76 has attaching ends much like the balance, for example, the angular part 83 for the underside of the frame head 15, and extension end 84 for the 55 frame side 12.

In Fig. 4 a cord fastener is shown which may be used on new window sash 90 (Fig. 3) equipped with wire cable 91. This is a simple plate 92 with inverted key-hole slot 93 and a screw hole 94 for screw 95. A knot 96 in the cable is sufficient to secure the cable. Where sash is already grooved for window rope, such as used for sash weights, the special fitting of Fig. 5 may be used. This has a curved body 97 to fit the groove in the sash; a sort of key-hole slot 98, a cover lug 99 for the top of the groove, with a hole 100 therein for the cable 101. A screw hole 102 is formed in the body of the fixture. Hole 100 is large enough to receive the knotted end of the cable 101, and the bayonet slot 98 is open in the area of the curved body to receive the knot while the sash equipped with this fastener is already in mounted position in the frame. 70

Where the loop 60 is used in the preferred 75

manner for attaching a single cable to the drum to provide equally tensioned lengths of cable, devices like those of Figs. 4 and 5 are suitable for both sides of the sash. The ends are affixed to 5 the sash, the slack taken up from the points of attachment, through the pulley fixture, up to the cord-block on the drum. All the slack is pushed through holes 58 in the cord block to produce even tension, and then the wound drum is permitted to unwind until it takes up all the slack 10 on the loop side of the cord block. This produces quick and permanent adjustment to equalize the tension.

However, where it may be desirable for any 15 reason to run two cords, each fastened to the drum 40 independently, there should be some means readily to equalize the tension. This may be provided by a device at the sash like that in Fig. 6. The sash 103 is grooved at 104 to receive 20 the device which comprises a screw or stud 105 carried by the sash over which the end of the cord 106 is looped. A plate 107 at the top of the sash is secured thereto by screw 108, and has a hole 109 through which the cord 106 passes. The 25 plate also carries a screw-headed shaft 110 freely turnable in the plate, pointing toward stud 105 and threaded at its lower end, on which it bears a nut-device 111, held from turning by the sides of slot 104. The nut carries the end of cable 106. 30 By turning the screw-headed shaft, the nut can be raised to take up tension in the cord. This adjusting attachment may be used also where a looped cable is originally adjusted with equal tension, to take up or let out cord where the cord 35 may have stretched in the unequal lengths.

The balance device is an assembly calculated to be permanent, and so constructed. It is therefore of importance that the spring 41 be of high quality, protected from exposure to corrosion, and 40 of structure limiting a tendency to break. Spring steel, when sharply bent, or when drilled with holes for securing it, is greatly weakened, and presents a potential danger spot. The structure of long or rounded curves to provide the hook 51, 45 and the eye 52 is therefore of considerable importance in connection with long life of the device.

Balances of such intended permanence heretofore have presented difficulty in improper reversal 50 of drum, or back-running, when the spring is not in tension. The slotted post 35 has been used heretofore, but with a structure in the spring to engage with it, such that the spring may slip out in back-running. By the large eye 52 the spring is 55 non-insertable and non-removable through the slot, and must be secured in the post axially through the end of it.

The spring 41 is merely exemplary of spring power means to actuate the cable drum 40. As a 60 matter of economy and compactness, it is mounted inside the drum. It is therefore to be understood that it may be located elsewhere, for example outside the drum, the toothed wheel 42 being a suitable gear for an operating connection. For heavy sash, where the size of the drum cannot house a sufficiently large drum, such external power means may be applied by gearing to the drum, or in the same way auxiliary power 65 may be added to the spring inside the drum.

70 By turning Fig. 7 to its side, making member 13 a head and member 15 a frame side, it will be seen that the balance may be installed in the side as well as the head.

Not only does the present invention concern 75 the structure of the balance, but it also involves

the whole assembly of frame, sash, cable, balance, and pulley fixture. The various features of the invention are of course subject to numerous modifications and changes, falling within the scope of the invention as set forth in the appended 5 claims.

I claim:

1. A sash balance comprising in combination a housing adapted to be mounted in a window frame head by a side of the window frame, a fixed 10 axle in said housing, a hollow cable drum in said housing rotatable on said axle, and open only at the bearing on said axle to provide a substantially dust proof interior, a spiral spring in said drum connecting the axle and the interior of the drum 15 to rotate the drum, flanges on the ends of said drum to guide and retain cable on the drum, one of said flanges having teeth thereon, a detent for locking the drum with the spring partly wound, means for mounting the detent for manual move- 20 ment in locking engagement with the teeth of the drum, said spring acting through the drum to hold said detent in engagement with the drum, and said detent being automatically removed from its holding position upon reverse rotation of the 25 drum against the force of the spring, means on the surface of the drum for holding cable for winding two lengths thereof simultaneously on the drum, the drum being located in the housing to deliver one length along the said window frame 30 side, and an idler pulley in the housing for guiding the other length under the frame head toward the opposite frame side.

2. In a sash balance a fixed axle, a closed hollow cable drum rotatable on said axle and open 35 to the interior only by the clearance at said axle, a spiral spring inside the drum, one end of the spring being attached to the axle and the other end being attached to the interior of the drum for winding and operating the drum, said drum 40 having a generally cylindrical contour at the exterior as a winding surface for cable and being recessed inwardly from said contour, a projecting part within the recess extending toward and not beyond said contour, said part being adapted 45 to secure the looped end of a single looped cable to the drum at a level within said contour and in region separated from the hollow interior of the drum.

3. In a sash balance having a rotatable drum 50 having a generally cylindrical surface for winding sash cable, a spring inside the drum for operating the drum, an axle on which the drum turns and to which one end of the spring is attached, said drum being substantially sealed 55 against dirt and dust except for the clearance at said axle, and a projecting part on the surface of the drum having two holes therethrough opening on one side to receive cable wrapped on the drum, whereby a cable length may pass into one hole 60 and return through the other to secure the cable to the drum, the surface of the drum being recessed to support said projecting part, and said projecting part lying within the contour of the generally cylindrical winding surface. 65

4. In a sash balance having a rotatable drum having a generally cylindrical surface for winding sash cable, a spring inside the drum for operating the drum, an axle on which the drum turns and to which one end of the spring is attached, said drum being substantially sealed against dirt and dust except for the clearance at said axle, and a projecting part on the surface of the drum having a hole therethrough opening to receive cable wrapped on the drum whereby 70 75

cable may be secured to the drum after entering said hole, the surface of the drum being recessed to support said projecting part, and said projecting part lying within the contour of the generally cylindrical winding surface.

5. A sash balance comprising in combination a housing adapted to be mounted in a window frame, a fixed axle in said housing, a hollow cable drum in said housing rotatable on said axle, a spiral spring in said drum connecting the axle and the drum, permitting rotation of the drum in a spring-winding direction and in a spring-unwinding direction, means to attach cable to

be wound on said drum, circularly disposed teeth concentric with and turning with said drum, a detent for locking the drum with the spring partly wound, means for mounting the detent for manual movement in locking engagement with the teeth of the drum, said spring acting through the drum to hold said detent in engagement with the drum, and said detent being automatically removed from its holding position upon reverse rotation of the drum against the force of the spring. 5

GILBERT L. HUFF.
